UNITED STATES PATENT OFFICE

WILLIAM L. MCGRATH, OF ELMIRA, NEW YORK, ASSIGNOR TO ECLIPSE MACHINE COMPANY, OF ELMIRA HEIGHTS, NEW YORK, A CORPORATION OF NEW YORK

ENGINE STARTER

Application filed October 16, 1925, Serial No. 62,817. Renewed October 9, 1931.

My invention relates to means for starting engines such as internal combustion engines and more particularly to that part known as the drive or transmission, which is located 5 between the prime mover and the engine to be started. The object of my invention is to provide a simple and efficient form of drive whose advantages in construction and mode of operation will be apparent from the 10 description hereinafter given.

In the drawings, Figure 1 is an elevation of an engine starter embodying my invention, showing the driving member or pinion in its normal position; Fig. 2 a similar view 15 but with parts thereof in section and showing the pinion in advanced position and abutting a member of the engine such as the flywheel thereof; Fig. 3 a view similar to Fig. 1 but showing the parts of the drive in operating 20 or engaged position; Fig. 4 a section on the line 4—4 of Fig. 1; Fig. 5 an end view of the pinion detached, and Fig. 6 a detail view of one of the connectors.

My invention may partake of different 25 forms and in the present instance I have illustrated and will hereinafter describe a construction which efficiently embodies and carries out my invention. Referring to this embodiment, in which I have shown a prime 30 mover, the latter consists of an electric motor 1 having an extended armature shaft 2 on which the drive or transmission is mounted and by which it is driven. The drive comprises a hollow shaft or sleeve 3 fitting 35 upon the driving or armature shaft 2 and terminating at its outer end in an enlargement or driving head 4 which is removably secured to such shaft in suitable manner as by means of the screw 5 threaded into such 40 head and passing through the shaft 2, as shown in Fig. 2.

A driving member which is here in the form 45 of a pinion 6 is mounted upon the sleeve 3 for longitudinal movement thereof and rotary movement therewith, in the present instance through a splined connection. To this end a sleeve 3 is provided partway of its length with a longitudinal key or spline 7 and the bore of the pinion is provided with 50 keyway 8 of considerable width or extent as

compared with the width of the key or spline 7, as clearly illustrated in Figs. 4 and 5.

The driving member or pinion is connected with the driving head 4 of the sleeve by connectors here in the form of a pair of strips 55 9 made of suitable resilient material such as spring metal, whose ends are pivotally secured to the head 4 and the disk 10 of the pinion on opposite sides thereof by suitable means such as the screws 11, whereby the 60 pinion is properly positioned in the operation of the drive.

Describing a cycle of operation of my drive and starting with the normal or idle position illustrated in Fig. 1, when the starting motor 65 1 is energized and its armature shaft rotated, the sleeve 3 will likewise be rotated but the pinion will not rotate owing to its inertia. This will cause the end of the connector attached to the sleeve to tend to approach the 70 similar attachment on the pinion disk and therefore the pinion will be pushed longitudinally of the sleeve so that the connecting points remain at a substantially constant distance apart. In this instance the parts are 75 so proportioned and arranged that when the pinion reaches the position in mesh with the engine member such as the flywheel 12, as shown in Fig. 3, the rotation of the sleeve will have brought the spline 7 into contact 80 with the side of the keyway 8 to drivingly connect the motor with the engine member.

When the engine starts on its own power the excess speed of rotation imparted by the flywheel to the pinion will reverse the operation above described and will cause the pinion to demesh and the parts to assume their normal position.

In the event that the pinion teeth and flywheel teeth should abut end to end, the pinion 90 will be stopped in its longitudinal movement but rotation of the sleeve will continue until, as above described, the spline 7 drivingly contacts the side of the keyway 8. The parts will then be in the position as shown in Fig. 2, 95 and as the distance between the attachment points of the connectors has thereby become less than the normal length of such connectors, these resilient connectors will have become deformed as shown, and will urge the 100

pinion into mesh with the flywheel as soon as rotation is imparted to it from the sleeve through the spline and keyway drive as above described, inasmuch as this rotation carries the tooth of the pinion out of abutting relation and into register with the space between the flywheel teeth, whereupon the parts will assume the position shown in Fig. 3.

I claim:

- 10 1. An engine starter drive including a rotatable driving shaft, a driving member mounted thereon for longitudinal movement into engagement with a member of the engine to be started and for limited rotary movement relative thereto from normal position, and spring-metal strips having effective lateral rigidity of longitudinal flexibility which are connected to the shaft and driving member and are tensioned in event of abutment of the driving and engine members until said driving shaft positively turns the driving member into proper engagement with the engine member.
- 15 2. An engine starter drive including a rotatable driving shaft, a driving member mounted thereon for longitudinal movement into engagement with a gear member of the engine to be started and for limited rotary movement relative thereto from normal position, said driving member comprising a pinion having a disk at one end, and connectors connected with the shaft and disk for positioning the driving member and arranged to yield to permit said shaft to positively turn said pinion member into registry with the engine gear member in event of non-registering abutment of said members.
- 20 3. An engine starter drive including a motor-driven power shaft extending freely over and beyond a gear of an engine to be started, a driving shaft or sleeve mounted on said power shaft and at its outer end secured thereto for rotation therewith, a driving pinion mounted on said driving shaft for longitudinal movement thereon inwardly into engagement with said engine member and for limited rotary movement relative thereto from normal position, and resilient means connected between the outer end of said driving shaft and said driving pinion adapted and arranged to advance the same when said driving shaft is rotated and to be tensioned in event of abutment of the driving pinion and said engine member.
- 25 4. An engine starter drive including a rotatable driving shaft having a longitudinal key, a driving member mounted on such shaft and having a keyway of a predetermined width greater than the width of the key, and means connecting in all positions the shaft and driving member for positioning the latter normally with the rear side of said keyway adjacent to the key.
- 30 5. An engine starter drive including a rotatable driving shaft having a longitudinal key, a driving member mounted on such shaft and having a keyway of a predetermined width greater than the width of the key, and connectors of predetermined length and connected at their ends to the shaft and driving member and normally positioning said driving member with its keyway rotarily advanced relative to the key.
- 35 6. An engine starter drive including a rotatable driving shaft, a driving pinion mounted for longitudinal movement relatively thereto to engage when advanced a gear member of the engine to be started, means for lost-motion rotary connection between said pinion and shaft, and connecting means between said shaft and pinion arranged for longitudinal advancement of the pinion when the shaft is rotated and yieldable to permit the shaft to take up said lost-motion and positively rotate the pinion in event of non-registering abutment of the teeth of said pinion and engine-gear.
- 40 7. An engine starter drive including a rotatable driving shaft, a driving pinion mounted thereon for longitudinal movement to engage when advanced a gear member of the engine to be started, means establishing lost-motion rotary connection between said pinion and shaft, and resilient connections between said shaft and pinion adapted and arranged to longitudinally advance the pinion when the shaft is rotated, to substantially take up said lost-motion in advancing said pinion to gear-meshing position and to yield for permitting the shaft to take up the lost-motion and positively rotate the pinion in event of non-registering abutment of the teeth of said pinion and gear.
- 45 8. An engine starter drive including a rotatable driving shaft, a driving pinion mounted thereon for longitudinal movement to engage when advanced a gear member of the engine to be started, means establishing lost-motion rotary connection between said pinion and shaft, and resilient connections between said shaft and pinion adapted and arranged to longitudinally advance the pinion when the shaft is rotated, to substantially take up said lost-motion in advancing said pinion to gear-meshing position and to yield for permitting the shaft to take up the lost-motion and positively rotate the pinion in event of non-registering abutment of the teeth of said pinion and gear.
- 50 9. In an engine starter drive, a rotary shaft, a pinion slidably mounted thereon for movement into and out of mesh with a toothed member of an engine to be started, means for shifting and driving the pinion from said shaft including a plurality of leaf spring members spirally disposed, anchored at one end of said shaft, and connections between the spring members and the pinion whereby relative rotation of the shaft and pinion causes the pinion to be pushed into mesh with the engine gear and to be drawn out of mesh therewith.
- 55 10. In an engine starter drive, a rotary shaft, a pinion slidably mounted thereon for movement into and out of mesh with a toothed member of an engine to be started, means for shifting and driving the pinion

key, a driving member mounted on such shaft and having a keyway of a predetermined width greater than the width of the key, and resilient means connecting in all positions the shaft and driving member for positioning the latter normally with the rear side of said keyway adjacent to the key.

70 75 80 85 90 95 100 105 110 115 120 125 130

6. An engine starter drive including a rotatable driving shaft having a longitudinal key, a driving member mounted on such shaft and having a keyway of a predetermined width greater than the width of the key, and connectors of predetermined length and connected at their ends to the shaft and driving member and normally positioning said driving member with its keyway rotarily advanced relative to the key.

7. An engine starter drive including a rotatable driving shaft, a driving pinion mounted for longitudinal movement relatively thereto to engage when advanced a gear member of the engine to be started, means for lost-motion rotary connection between said pinion and shaft, and connecting means between said shaft and pinion arranged for longitudinal advancement of the pinion when the shaft is rotated and yieldable to permit the shaft to take up said lost-motion and positively rotate the pinion in event of non-registering abutment of the teeth of said pinion and engine-gear.

8. An engine starter drive including a rotatable driving shaft, a driving pinion mounted thereon for longitudinal movement to engage when advanced a gear member of the engine to be started, means establishing lost-motion rotary connection between said pinion and shaft, and resilient connections between said shaft and pinion adapted and arranged to longitudinally advance the pinion when the shaft is rotated, to substantially take up said lost-motion in advancing said pinion to gear-meshing position and to yield for permitting the shaft to take up the lost-motion and positively rotate the pinion in event of non-registering abutment of the teeth of said pinion and gear.

9. In an engine starter drive, a rotary shaft, a pinion slidably mounted thereon for movement into and out of mesh with a toothed member of an engine to be started, means for shifting and driving the pinion from said shaft including a plurality of leaf spring members spirally disposed, anchored at one end of said shaft, and connections between the spring members and the pinion whereby relative rotation of the shaft and pinion causes the pinion to be pushed into mesh with the engine gear and to be drawn out of mesh therewith.

10. In an engine starter drive, a rotary shaft, a pinion slidably mounted thereon for movement into and out of mesh with a toothed member of an engine to be started, means for shifting and driving the pinion

from said shaft including a plurality of leaf spring members spirally disposed, connections between said spring members and said shaft, and connections between the spring members and said pinion whereby relative rotation of the shaft and pinion causes the pinion to be pushed by said springs into mesh with the engine gear and to be drawn out of mesh therewith, said springs being arranged to yield during the meshing operation in case a tooth of the pinion abuts a tooth of the engine gear.
